MOTH BAG

Earl A. Lewis, Chicago, Ill.

Application February 23, 1933, Serial No. 658,188

11 Claims. (Cl. 206—10)

This invention relates to improvements in moth bags and, more especially, a bag or container adapted to enclose clothing or other material to be fumigated for the purpose of destroying moths, 5 larvae, eggs, and the like therein.

Among the features of my invention is the provision of such a device which is substantially gas-tight and which can be quickly and readily opened and closed for the purpose of placing 10 clothing therein and removing the same therefrom.

My improved device is so constructed that a volatile liquid can be readily inserted therein in a suitable container so that when the bag is 15 closed, the gases therefrom will fill the bag and permeate the clothing therein to destroy insect life of the character described.

Other features and advantages of my invention will appear more fully as I proceed with 20 my specification.

In that form of device embodying the features of my invention shown in the accompanying drawings—

Fig. 1 is a view in perspective; Fig. 2 is a 25 view in perspective of the upper portion of the bag showing the same in broken lines and removed from the cover; Fig. 3 is a fragmentary view of one end of the wire frame inside of the upper edge of the bag; Fig. 4 is a vertical 30 sectional view showing the means for attaching the bag to the cover; Fig. 5 is a view of the cover and the upper end of the bag partly in vertical section and partly in side elevation; Fig. 6 is a bottom plan view of the cover; and Fig. 7 35 is a view of the cover and the upper part of the bag partly in vertical section and partly in end elevation.

As shown in the drawings, the device includes 40 in general a cover A and a detachable bag B. The cover A is here shown substantially semi-cylindrical in shape with its ends closed and the same may be made out of any suitable material, for example, sheet metal. Such cover, of 45 course, may take a variety of shapes, sizes and proportions and still be within the spirit of my invention. It is only necessary that the same be substantially gas-tight and be provided with a rigid periphery or edge to which the upper edge of the bag may be detachably secured to form 50 a substantially gas-tight joint.

The top of the cover A is provided with a 55 hook 10 for suspending the same from a suitable pole or other support. Inside of the cover along the top is provided a trough-like casing 11 adapted to contain suitable absorbent material 12.

The ends of this casing are provided with perforations 13. The top of the cover A is provided with a filler spout or neck 14 opening into the interior of the trough 11 and adapted to be closed by a removable cap 15. In the practice of 60 the invention a suitable moth-killing volatile liquid can be poured into the neck 14 to wet the absorbent material 12. The fumes given off by this liquid as the same vaporizes escape through the perforations 13 to fill the bag and 65 permeate the clothing therein to destroy moth life, and the like, as described above.

The inside of the cover A is also provided with a cross bar 16 adapted to support hangers of a well-known type upon which clothing in 70 the bag may be suspended.

Around the margin on the inside, the cover A may have a suitable bead 17 to assist in positioning the upper edge of the bag therein to form a substantially gas-tight joint. Each end 75 of the cover A is provided with a vertical slot 18 in the center to receive the projecting lugs on the frame in the upper edge of the bag to be hereinafter described. As shown in Fig. 2, these lugs are indicated by 19 and each end of 80 the cover A carries a hook or catch 20 pivoted at 21 adapted to be swung to engage the lugs 19 to hold the bag in position, as shown by the solid lines in Fig. 2, or moved to released position, as shown by the broken lines in Fig. 2, which 85 permit disengagement of the bag from the cover.

The bag indicated by B is preferably made of some suitable flexible substantially gas-proof material such as, for example, rubberized cloth, paper, cellophane or the like. The same is substantially rectangular in shape and is large enough to accommodate the number of articles to be suspended from the hanger wire 16 in the cover. The flexible material of which the bag is made is here indicated by 22. The upper edge 90 of this material is formed into a hem 22^a enclosing a rectangular wire frame 23 provided with the projecting lugs 19, 19 at each end, as described above. The extreme end of each of the lugs is preferably provided with a knob 19^a to 95 assist in grasping the bag.

In the practice of the invention, clothing on suitable hangers are first supported from the wire 16. The upper end of the bag is then grasped by the handles 19^a and drawn up over the clothing. The lugs 19 are inserted in the slots 18 and the catches 20 swung to engage the same. The upper edge of the bag preferably fits rather snugly inside of the lower edge of the cover and is designed to be positioned just under and 100 105 110

adjacent the internal bead 17, the latter assisting in holding the upper edge of the bag and the rigid frame 23 in correct position to give a substantially gas-tight joint between the lower edge 5 of the cover and the upper edge of the bag. Volatile moth-destroying liquid is then poured into the filler neck 14 and the cap 15 put in place. Fumes escaping through the holes 13 will fill the bag to permeate the clothing and 10 destroy moth life, as described above.

While I have shown and described certain embodiments of my invention, it is to be understood that it is capable of many modifications. Changes, therefore, in the construction and 15 arrangement may be made without departing from the spirit and scope of the invention as disclosed in the appended claims, in which it is my intention to claim all novelty inherent in my invention as broadly as permissible, in view of the 20 prior art.

What I regard as new, and desire to secure by Letters Patent, is:

1. A moth bag, including: a substantially gas-tight cover with a rigid edge; means for suspending said cover from a support; means attached 25 to the underside of the cover for supporting clothing; means attached to the underside of the cover for containing a volatile substance, said means permitting the escape of gases from said substance; a bag with a rigid upper edge adapted to cooperate with the edge of the cover to form a substantially gas-tight joint; and means for detachably securing the upper edge of the bag to the edge of the cover.

2. A moth bag, including: a substantially gas-tight cover with a rigid edge; means for suspending said cover from a support; means attached to the underside of the cover for supporting clothing; means attached to the underside of the cover for containing a volatile substance, said means permitting the escape of gases from said substance; a flexible bag with a rigid upper edge adapted to cooperate with the edge of the cover to form a substantially gas-tight joint; and means for detachably securing the upper edge of the bag to the edge of the cover.

3. A moth bag, including: a substantially gas-tight cover with a rigid edge; means for suspending said cover from a support; means attached to the underside of the cover for supporting clothing; means attached to the underside of the cover for containing a volatile substance, said means permitting the escape of gases from said substance; a bag; a rigid frame in the upper edge of the bag; and means for detachably securing said frame to the cover to cause the upper edge of the bag to make a substantially gas-tight joint with the edge of the cover.

4. A device as claimed in claim 1, in which 60 the means for containing the volatile substance includes a perforated receptacle and absorbent material in said receptacle.

65

70

75

5. A device as claimed in claim 1, in which the means for containing the volatile substance includes a perforated receptacle having a filling opening to the outside of the cover, and absorbent material in said receptacle.

6. A device as claimed in claim 1, in which the means for containing a volatile substance includes a perforated receptacle having a filling opening extending to the outside of the cover.

7. A moth bag, including: a substantially gas-tight semi-cylindrical cover with a rigid lower edge; means for suspending said cover from a support; means inside of the cover for supporting clothing; means inside of the cover for containing a volatile substance, said means permitting escape of gases from said substance; a bag with a rigid upper edge adapted to cooperate with the lower edge of the cover to form a substantially gas-tight joint; and means for detachably securing the upper edge of the bag to the edge of the cover.

8. Apparatus as claimed in claim 7, in which the ends of the cover are provided with slots and in which the upper edge of the bag is provided with a rigid rectangular frame having lugs adapted to be inserted in the slots in the cover, and means for detachably securing said lugs in said slots.

9. A moth bag, including: a substantially gas-tight cover of substantial area with a rigid edge; means for suspending said cover from a support; means attached to the underside of the cover for supporting clothing; means attached to the underside of the cover for containing a volatile substance, said means permitting the escape of gases from said substance; a bag with a rigid upper edge adapted to cooperate with the edge of the cover to form a substantially gas-tight joint; and means for detachably securing the upper edge of the bag to the edge of the cover.

10. A moth bag, including: a substantially gas-tight cover of substantial area with a rigid edge; means for suspending said cover from a support; means attached to the underside of the cover for supporting clothing; a bag with a rigid upper edge adapted to cooperate with the edge of the cover to form a substantially gas-tight joint; and means for detachably securing the upper edge of the bag to the edge of the cover.

11. A moth bag, including: a substantially gas-tight cover with a rigid edge; means for suspending said cover from a support; means attached to the underside of the cover for supporting clothing; a bag with a rigid upper edge adapted to cooperate with the edge of the cover to form a substantially gas-tight joint; and means for detachably securing the upper edge of the bag to the edge of the cover.
